UNITED STATES PATENT OFFICE

FRED ASHWORTH, OF BEVERLY, MASSACHUSETTS, ASSIGNOR TO UNITED SHOE MACHINERY CORPORATION, OF PATERSON, NEW JERSEY, A CORPORATION OF NEW JERSEY

SEWING MACHINE

Application filed May 19, 1920, Serial No. 382,558. Renewed January 22, 1926.

The present invention relates to sewing machines and more particularly to lock stitch outsole shoe sewing machines which are provided with a curved hook needle and a curved awl.

The object of the present invention is to simplify and improve the construction and mode of operation of sewing machines particularly of the type referred to. With this object in view the features of the present invention consist in certain constructions, arrangements and combinations of parts hereinafter described and claimed, the advantages of which will be obvious to those skilled in the art.

The several features of the present invention will be clearly understood from the following description and accompanying drawings in which:

Figure 1 is a front elevation of a lock stitch outsole shoe sewing machine embodying the features in their preferred form; Fig. 2 is a right side elevation; Fig. 3 is a face view of a stop cam and its follower forming parts of the stop mechanism of the machine; Fig. 4 is a rear elevation of the machine; Figs. 5 and 6 are right and left side elevations on an enlarged scale of the head of the machine; Fig. 7 is a vertical sectional view taken substantially on the line 7—7 of Fig. 1; Fig. 8 is a detailed sectional view of a portion of the work feeding mechanism taken on the line 8—8 of Fig. 9; Figs. 9 and 10 are sectional plan views taken on the lines 9—9 and 10—10, respectively, of Fig. 5; Fig. 11 is an enlarged front elevation of a portion of the machine illustrating particularly the take-up, pull-off, thread locking and looper mechanisms, with the take-up shown at the limit of its take-up movement; Fig. 12 is a detailed front elevation of the take-up shown at the limit of its retracting movement; Fig. 13 is a vertical sectional view of a portion of the presser foot actuating mechanism with the parts shown in the position that they assume when the needle is at the limit of its loop drawing stroke; Fig. 14 is a similar view of the presser foot actuating mechanism with the parts shown in the position they assume immediately after the needle has reached the

limit of its work piercing stroke; Fig. 15 is a detailed sectional view taken on the line 15—15 of Fig. 9; Fig. 16 is a detailed sectional view taken on the line 16—16 of Fig. 5; Fig. 17 is a vertical sectional view, partly in elevation, of the shuttle mechanism and other stitch forming devices looking toward the right of the needle; Fig. 18 is a front view of a portion of the shuttle mechanism illustrated in Fig. 17; Fig. 19 is a view similar to Fig. 17 but looking toward the left, and also showing the bobbin case in elevation and the mounting of the edge gage and channel or fudge knife; Fig. 20 is a front view, partly in section, of a portion of the machine showing particularly the parts on which are mounted the needle, awl, thread hook, fudge knife and edge gage; Fig. 21 is a detailed transverse sectional view of the bobbin case looking toward the rear of the machine; Fig. 22 is a rear elevation of the bobbin case; Fig. 23 is a vertical sectional view of a portion of the driving and stopping mechanism of the machine taken on the line 23—23 of Fig. 4; Fig. 24 is a sectional view taken on the line 24—24 of Fig. 23; and Fig. 25 is a sectional plan view taken on the line 25—25 of Fig. 23.

In the sewing machine illustrated in the drawings, the work is fed by means of a work support and presser foot while the needle and awl are out of the work. At the completion of the feeding operation the awl is actuated to pierce the work and as the awl retracts the needle closely follows the awl through the work. During the feeding operation and during the described movements of the awl and needle, the work is firmly clamped on the work support by the presser foot. At the limit of the work piercing stroke of the needle, the pressure of the presser foot on the work is relieved and the presser foot and work support are returned to their initial position whereupon the presser foot is again caused to clamp the work firmly on the work support. As the needle is in the work during the back feeding or retraction of the work support and presser foot, there is no danger of the work becoming dislodged by the work support and presser foot being dragged over the work, and the needle is supported at this

time by the needle guide which is advanced to a position in engagement with the work. When the work support and presser foot have been retracted and the presser foot is caused to clamp the work on the work support, the loop drawing stroke of the needle is initiated.

The construction of the work support and presser foot, and their actuating mechanism is such that there is no danger of any back lash occurring even when these parts become worn with use. The feeding of the work by means of the work support and presser foot permits the awl and needle to be in alinement at all times so that there is no danger of the needle failing to accurately enter the hole made by the awl as frequently occurs in machines in which the awl is employed to feed the work.

20 The work support is indicated at 2 and the presser foot is indicated at 4 (Figs. 1, 7 and 10). The work support is shaped as usual to enter the crease between the welt and the upper and to cooperate with and edge gage 6 to guide the work. The work support is provided with the usual slot 8 through which the needle and awl work and through which a fudge or channel knife 10 for the welt extends. The work support is centrally 25 formed on a curved bar 12, the ends of which are secured to arms 14 projecting forwardly from a work support carrier 16.

It is customary in sewing about the forepart of a shoe to guide the shoe by means of 30 the edge gage but as it is desirable, particularly on women's shoes, to make the line of stitches closer to the upper at the shank than about the forepart of the shoe, the edge gage is retracted when the shank is reached to permit the shoe to be guided by the work support. In the illustrated machine, in order that the line of stitches may be made as close as desired to the upper at the shank of the shoe, the work support has provision for adjustment in the plane of its work supporting surface. To this end, the curved bar 12 is 40 adjustably secured to the arms 14 by means of horizontal pins 18 projecting from the ends of the curved bar engaging split clamping 45 collars formed on the ends of the arms 14. The arms 14 are spaced at a distance to permit the looper 20 and parts of the actuating mechanism for the needle and awl to operate between them.

50 In order that the work support may be actuated to feed the work, the carrier 16 is pivotally mounted on a vertical pin 22 supported by the frame of the machine and spaced at a distance from the end of the work support (Figs. 6, 7, 8, 9 and 10). The forward end of the carrier 16 is supported by means of a bracket 24 that is provided with a flattened surface with which flattened surfaces formed on the under sides of the arms 14 are in sliding engagement. In order to move the

presser foot 4 laterally with the work support to feed the work, it is formed on the end of a lever 26 which is pivotally mounted on an upright bracket 28 projecting from one of the arms 14.

70 The carrier 16 is moved about its pivot to feed the work by means of horizontally reciprocating blocks 30 (Figs. 7, 8 and 9) which are pivotally mounted on the ends of a vertical pin 32. The lower block 30 engages a radial groove 34 formed in the carrier 16 and the upper block 30 engages a groove 36 in a relatively fixed block 38, the groove 36 being at an angle to the groove 34. With this construction, it will be understood that by actuating the pivot pin 32 to move the blocks 30 longitudinally of the grooves a lateral feeding movement will be imparted to the work support and presser foot. The pivot pin 32 is actuated to impart the desired feeding movements to the work support and presser foot by means of a link 40 on the forward end of which the pivot pin is formed. The rear end of the link 40 is pivotally connected to an arm 41 secured to the upper end of a vertical rock shaft 42 mounted in the frame. An arm 43 is secured to the lower end of the rock shaft 42 and is provided with a cam roll which engages a groove in a cam disk 44 carried by a driving shaft 46 of the machine.

80 In order to adjust the length of the feed, the grooved block 38 is adjustable to vary the relative angular positions of the grooves 34 and 36. The block 38 is pivotally mounted by means of a stud 48 projecting from the top thereof engaging a socket bearing in the frame of the machine, and its rear end is pivotally connected to the bifurcated end of a sleeve 50. The other end of the sleeve 50 is split and embraces the rear end of a rod 52 (Fig. 15), the sleeve being securely clamped to the rod by means of a bolt 54. The rod 52 is screw-threaded through a sleeve 56 mounted to turn in a bearing in the frame and is held from longitudinal movement by nuts 58 threaded on its inner end and by a pinion 60 secured to its forward end. By turning the sleeve 56, the block 38 may be adjusted to vary the length of the feed. In order that the operator may conveniently effect such adjustment of the block 38, the sleeve 56 is adapted to be turned by means of a hand lever 62 (Figs. 1 and 10) secured to the right hand end of a rock shaft 64 mounted in the frame. The connection between the sleeve 56 and the hand lever 62 comprises a gear segment 66 engaging the pinion 60, which gear segment is formed on the end of an arm secured to the rock shaft 64. The grooved block 38 is adapted to be adjusted independently of the hand lever 62 to vary the length of the feed. This may be accomplished by loosening the clamping bolt 54 and turning the rod 52 in the sleeve 56, a screw driver slot 90

being provided in the end of the rod for this purpose.

During the action of the stitch forming devices in forming a stitch, and during the feeding operation, the presser foot is locked in clamping engagement with the work so that the work is tightly clamped between the presser foot and work support. At the end of the feeding operation, however, the presser foot is unlocked and is caused to lightly engage the work by means of a coiled spring 70 connected with the rear end of the presser foot lever 26 so that the presser foot will offer practically no resistance to the back feeding or retracting movement of the work support and presser foot. At the end of the retracting movement of these parts, the presser foot is pressed into engagement with the work with a comparatively heavy pressure so as to clamp the stock firmly against the work support and is then locked in position. The presser foot remains locked until the end of the feeding operation when it is again unlocked and the cycle of operations repeated.

The locking mechanism for the presser foot comprises a wedge block 72 (Figs. 7 and 10) the upper end of which engages the rear end of the presser foot lever. The lateral faces of the wedge block 72 are preferably arranged at a relatively small acute angle to each other, as shown in Fig. 7. A guide plate 74 secured to the frame is arranged to engage the forward face of the wedge block and acts to limit the movement of the wedge block laterally in one direction. A longitudinally movable locking wedge block 76 is arranged to engage the rear face of the wedge block 72 to lock the same from downward movement. The locking wedge block 76 is mounted to slide on a vertical rod 78 secured to the frame. At the proper times during the operation of the machine, the locking wedge block is moved upwardly and acts through the wedge block 72 to clamp the presser foot upon the work. The block 76 is thus moved upwardly by means of an arm 80, the forward end of which is bifurcated and is provided with studs or rolls that engage horizontal slots 82 in opposite sides of the block. The arm 80 is secured to a rock shaft 84 having one end journaled in the frame and its other end journaled in a bearing sleeve 86 held in a split collar 88 formed on the frame, by a bolt 90. The rock shaft 84 is urged in a direction to move the locking wedge block 76 upwardly by means of a spring 92 coiled about the shaft and having one end connected to the arm 80 and its other end secured to the bearing sleeve 86. In order to vary the clamping pressure of the presser foot on the work, the tension of the spring 92 is adjustable, and this is accomplished by loosening the bolt 90 and turning the bearing sleeve

86, a collar or nut being formed on the inner end of the sleeve for this purpose.

The presser foot is unlocked when the needle has reached the limit of its work piercing stroke, preliminary to the back feeding of the work support and presser foot, by mechanism connecting the rock shaft 84 with the needle actuating mechanism hereinafter described. This mechanism comprises a friction disk 94 (Figs. 10, 13 and 14) secured to the left end of the rock shaft 84, the periphery of which is adapted to be engaged by a friction shoe 96 to turn the rock shaft 84 in the direction to lower the locking wedge block 76 in opposition to the torsion spring 92. The shoe 96 comprises a link having one end pivoted on a pin 97 extending between the arms of a yoke 98, the lower ends of the arms being joined by a bar 99 and the upper ends of the arms being loosely mounted on the rock shaft 84 at opposite sides of the disk 94. The other end of the shoe 96 is pivotally connected with one end of a link 100 and the other end of the link 100 is pivotally connected with the free end of an arm 102 projecting from a rocking sleeve 103 mounted on a shaft or rod 104 secured to the frame, the rocking sleeve forming a part of the needle actuating mechanism, hereinafter described.

The friction shoe 96 is normally maintained in a certain position relatively to the cross bar 99 by means of a spring pressed plunger 105 mounted in a longitudinal aperture in the friction shoe and engaging the cross bar 99, the plunger acting to maintain a stop lug 106 formed on the lower end of the friction shoe in engagement with the cross bar. When the needle is at the limit of its loop drawing movement, the friction shoe 96 and the link 100 are substantially in alignment, as shown in Fig. 13. During the work piercing stroke of the needle, the rocking sleeve 103 acts to swing the yoke 98 downwardly, the friction shoe being maintained by the plunger 105 in its normal position relatively to the cross bar 99 until the cross bar engages a yielding stop 108. The continued movement of the link 100 after the engagement of the cross bar 99 with the yielding stop 108 cooperates with the stop to turn the friction shoe about the pivot pin 97 against the action of the spring pressed plunger 105. This turning movement of the friction shoe brings an eccentric friction surface 107 formed on the shoe into engagement with the periphery of the disk 94, whereupon the continued movement of the link 100 acts through this engagement of the friction shoe with the friction disk to turn the shaft 84 in the direction to unlock the presser foot, which occurs near the limit of the work piercing stroke of the needle.

At the start of the loop drawing stroke of the needle, the rocking sleeve 103 is turned in the direction to swing the yoke 98 rearwardly

out of engagement with the yielding stop 108, thereby permitting the friction shoe 96 to resume its normal position relatively to the cross bar 99 and out of engagement with the friction disk 94 to permit the presser foot to again clamp the work on the work support. 5

The yielding stop 108 comprises a plunger rod 110 (Fig. 6) mounted to slide in an aperture in the frame and is urged rearwardly by 10 means of a spring 112 coiled about the rod and engaging a shoulder on the rod, the rearward movement of the rod being limited by adjustable stop nuts 114 threaded on the forward end thereof.

15 A treadle operated mechanism is provided to enable the operator to unlock and raise the presser foot and to release a thread locking device so that the work may be easily removed and the requisite amount of thread 20 pulled from the supply. This mechanism comprises a treadle rod 120 (Figs. 2, 5 and 10) which is pivotally connected at 122 to the free end of an arm 124 loosely mounted on the presser foot controlling shaft 84. The upper 25 end of the treadle rod 120 is pivotally connected with the rear end of a lever 126 pivoted on the machine frame and having its forward end arranged to engage the rear end of the presser foot lever 26. When the treadle 30 rod 120 is raised upon actuating the treadle mechanism, the arm 124 is swung upwardly and acts through the engagement of a forwardly projecting lug 128 on the hub thereof with a lug on the locking wedge block actuating 35 arm 80, to lower the locking wedge block 76 thereby unlocking the presser foot, the presser foot being then raised by the engagement of the lever 126 with the presser foot lever. The thread locking device that is released 40 at this time and its connection with the treadle rod 120 will be hereinafter described. Upon releasing the treadle mechanism, a coiled spring 130 connected with the treadle rod acts to depress the rod, thereby allowing 45 the shaft 84 to be turned by its spring in the direction to lock the presser foot in engagement with the work.

The needle 136, needle guide 138, awl 140, edge gage 6, fudge knife 10, and a thread 50 arm or hook 142 are all mounted for movement about a common axis (Figs. 17, 19 and 20). The needle and awl are carried by segments 144 and 146, respectively, which are arranged side by side between bracket arms 55 148 projecting from the frame of the machine. The needle segment 144 is journaled on the conical end of a pin 150 and is provided with a cylindrical hub 152 that is journaled in a sleeve 154 which in turn is journaled in the 60 left-hand bracket arm 148. The bearing pin 150 is screw-threaded through a coaxial aperture in the hub 156 of the awl segment 146 and is locked to the awl segment by means of a nut 158 threaded on its outer end. The hub 65 156 of the awl segment is journaled in the

right-hand bracket arm 148. The needle guide 138 projects from a flange 160 on the inner end of the sleeve 154 which flange is adjacent the needle segment. The thread arm or hook 142 is carried by a collar or segment 162 journaled on the sleeve 154 between the flange 160 and the left-hand bracket arm 148. The edge gage 6 and the fudge knife 10 are mounted on the free end of an arm or segment 164 which is loosely mounted on a bearing 70 166 formed on the right-hand bracket arm 148, and said arm 164 is interposed between the awl segment and a shoulder formed on said bracket arm. With this construction it will be apparent that the instrumentalities 75 above referred to are mounted in such a manner that the parts thereof will operate with certainty and smoothness and that the liability of the parts becoming worn with use will be reduced to a minimum. By adjusting the bearing pin 150 in the hub of the awl segment, any looseness of the parts may be readily taken up. 80

The needle and awl are actuated through lever and link connections with cranks 168 and 169 respectively mounted on the driving shaft 46, and these mechanisms are so constructed and arranged that the needle and awl operate with ease, certainty and smoothness and the mechanisms take up a minimum 95 amount of space in the machine. 90

In lock stitch outsole shoe sewing machines, it is desirable that the feeding devices shall be given as much time as possible to feed the work during a cycle of operations of the machine. In sewing machines of this type in which the work is fed by means of the work support and presser foot, it is obvious that the length of time that can be given to these parts to feed the work is dependent upon the 100 length of time that both the needle and awl are out of the work. In the illustrated machine the mechanisms for actuating the needle and awl are so constructed and arranged that the needle and awl are both out of the work 105 while their actuating cranks are travelling approximately 160°, thereby giving the work support and presser foot a comparatively long time to feed the work. 110

The needle and awl actuating mechanisms 115 in the illustrated machine are also constructed and arranged in such a manner that both the work piercing and retracting strokes of the needle and awl are made with rapidity, the needle closely follows the awl as the awl 120 retracts through the work and the needle is maintained at the limit of its work piercing stroke a sufficient length of time to give the work support and presser foot ample time to 125 return to their initial position.

The connection between the needle and its actuating crank 168 comprises a link 172 (Figs. 6 and 10) connecting the needle segment with an arm 174 projecting from the 130 rocking sleeve 103 that actuates the mecha-

- nism for unlocking the presser foot as hereinbefore described. The arm 174, the sleeve 103, and an arm 175 projecting from the sleeve constitutes a bell crank. The arm 175 of the bell crank is connected by a link 176 with one arm of a lever 178 pivotally mounted on a pin 179 secured to the machine frame. The other arm of the lever 178 is connected by a link 180 with the actuating crank 168. With this connection between the needle and its actuating crank, it will be apparent from an inspection of the drawings that an idle backward and forward movement is imparted to the needle at the limit of its loop drawing stroke, this idle movement of the needle being provided in order to maintain the needle out of engagement with the work the desired length of time and to cause the needle to operate in the proper timed relation to the awl. This result is due mainly to the arrangement of the lever 178 with relation to the bell crank 174—175, the arrangement being such that during the oscillating movement of the lever 178 in each direction the pivotal connection of the link 176 with the lever 178 crosses the line joining the pivot of the lever and the pivotal connection of the link 176 with the bell crank.
- It will also be apparent that an idle backward and forward movement of a sufficient duration is imparted to the needle at the limit of its work piercing stroke to give the work support and presser foot the desired length of time to return to their initial positions after feeding the work. This idle backward and forward movement of the needle, however, is only through a sufficient distance to raise the work slightly from the work support so that during the back feeding or retraction of the work support and presser foot the work support will not drag on the work, the backward part of the idle movement of the needle occurring at the start of the retraction of the work support and presser foot, and the forward part of the movement occurring at the limit of the retraction of the work support and presser foot, the latter part of the movement acting to again bring the work down upon the work support. This result is due mainly to the arrangement of the bell crank 174—175 with relation to the needle segment, the arrangement being such that during the oscillating movement of the bell crank in each direction, the pivotal connection of the link 172 with the bell crank crosses the line joining the pivot of the bell crank and the pivotal connection of the link 172 with the needle segment.
- The connection between the awl and its actuating crank 169 comprises a link 186 (Figs. 5 and 10) connecting the awl segment with the forward arm 188 of a bell crank having an elongated hub which is pivotally mounted on the rod 104. The rear arm 189 of the bell crank 188 is connected by a link 190 with the actuating crank 169. With this connection between the awl and its actuating crank it will be apparent that an idle backward and forward movement will be imparted to the awl at the limit of its retracting movement, this idle movement being provided in order to maintain the awl out of engagement with the work the desired length of time and to cause the awl to operate in the proper timed relation to the needle. This result is due mainly to the relation of the bell crank 188 to the awl segment, the arrangement being such that during the oscillating movement of the bell crank in each direction, the pivotal connection of the link 186 with the bell crank crosses the line joining the pivotal connection of the link with the needle segment and the pivot of the bell crank.
- During the work piercing stroke of the needle the needle guide is advanced into engagement with the work and is held in this position while the needle is at the limit of its work piercing stroke, in order to support the needle against any drag of the work support and presser foot on the work in returning to their initial position after feeding the work. The needle guide is advanced and held in advanced position by means of the needle segment (Fig. 17), which is connected by a coiled spring 191 with the carrier for the needle guide. During the loop drawing stroke of the needle the needle guide is retracted by the engagement of the rear end of the needle segment with a lug 194 on the needle guide carrier.
- It is frequently desirable in sewing about the shank of a shoe to retract the edge gage and fudge knife from the work and to lengthen the feed, and when the forepart of the shoe is reached to move the edge gage and fudge knife into operative engagement with the shoe and to shorten the feed. These operations are simultaneously effected in the illustrated machine by means of the hand operated lever 193 having its rear end pivotally mounted on the shaft 64 and having its forward end extending to a position where it is conveniently accessible to the operator (Figs. 2, 5 and 10). The connection between the hand lever 193 and the edge gage, fudge knife, and work feeding means is such that upon movement of the lever downwardly from the position shown in Fig. 5, the edge gage and fudge knife will be moved into operative engagement with the work and the length of the feed decreased, and upon movement of the lever in the opposite direction the edge gage and fudge knife will be retracted from the work and the length of the feed increased.
- The edge gage 6 is formed on the forward end of a lever pivotally mounted on a cap screw 196 between the head of the screw and the arm 164. The end of the cap screw 196

is reduced and extends through an aperture in the end of the arm 164 and is threaded into a block 198 on the inner side of the arm. The fudge knife 10 is adjustably secured to the arm 164 by being inserted in an aperture 200 formed by registering grooves in the arm and block 198 which are concentric with the axis of the arm. The rear end of the edge gage lever is pivotally connected to the upper arm 164 of a bell crank 202 pivotally mounted on a stud shaft 204. On the lower arm of the bell crank 202 (Figs. 5, 10 and 16), a block 206 is pivotally mounted which engages a cam groove in a segment 210 carried by the hand lever 193. The cam groove in the segment 210 is so arranged that upon movement of the hand lever 193 downwardly from the position shown in Fig. 5, the bell crank will be rocked in a direction to move the edge gage and fudge knife into operative engagement with the work, and upon movement of the hand lever upwardly, the edge gage and fudge knife will be retracted from the work.

In order that the length of the feed may be adjusted by the hand lever 193, the hand lever 62 for adjusting the length of the feed as hereinbefore described, is adapted to be connected to the hand lever 193. The lever 62 has a handle 211 pivotally connected with its end, and the handle is provided with a lug 212 which engages a locking recess in the hand lever 193 when the handle 211 is swung toward the hand lever 193, as shown in full lines in Fig. 10 of the drawings.

The edge gage and fudge knife may also be moved into and out of operative position without varying the length of the feed, and the length of the feed may be adjusted without changing the positions of the edge gage and fudge knife, by swinging the handle 211 outwardly to disconnect the hand levers 62 and 193, as shown by broken lines in Fig. 10, permitting the levers to be moved independently.

The amount of movement imparted to the edge gage and fudge knife and the amount of adjustment of the feed during a movement of the hand lever 193 a given distance may be relatively varied by an adjustment of the segment 210. To this end the lower end of the segment is pivotally mounted on a downwardly projecting lug on the hand lever 193 by means of a pin formed on the segment engaging an aperture in the lug. By turning the segment 210 on its pivot the amount of eccentricity of the cam groove in the segment 210 relatively to the shaft 64 may be varied and thereby the amount of movement imparted to the edge gage and fudge knife relatively to the amount of adjustment of the feed during a movement of the lever 193 may be varied. By adjusting the segment 210 so that its cam groove will be concentric with the shaft 64, it will be seen that no movement will be imparted to the edge gage and fudge knife

upon moving the hand lever 193. Such adjustment of the segment 210 about its pivot is effected by means of a rod 216 having its rear end pivotally connected to the upper end of the segment 210. The rod 216 extends through the handle of the lever 193 and its forward end is threaded into a nut 218 on the end of the handle (Fig. 2). The nut 218 is held from longitudinal movement so that by turning the nut the desired adjustment of the segment 210 can be effected.

The thread arm or hook 142 (Figs. 1, 6, 10, 17 and 20) which cooperates with the looper 20 to lay the thread in the barb of the needle in the usual manner is actuated by a cam disk 44 carried by the driving shaft 46. The connection between the thread hook and the cam disk 44 comprises a pinion 220 engaging gear teeth formed on the collar or segment 162 that carries the thread hook. The pinion 220 is engaged by a gear segment formed on the upper end of a lever 222 fulcrumed on a pin 224 secured to the machine frame. The lever is actuated by a cam roll 223 on the lower end thereof engaging a groove in the inner face of the cam disk 44.

The looper 20 comprises a tube through which the thread passes (Figs. 1, 6 and 11). Back and forth and transverse movements in a plane inclined slightly to the horizontal are imparted to the looper which combine to cause the looper to traverse a path about the needle. The looper is secured in a collar upon the upper end of a carrier 230 pivotally mounted on a pin 232 extending between ears projecting from a block 234. The back and forth movement is imparted to the looper by means of a yoke 236 having horizontal hubs 238, one of which is pivoted on the inner end of the stud shaft 204 and the other pivoted on a pin 239 secured to the frame of the machine. The yoke 236 is provided with a slot 240 that is engaged by a downwardly projecting tail piece 242 on the carrier 230. The yoke 236 is provided with a downwardly extending arm 244 having a cam roll 246 on its lower end which engages a cam groove in a face of the cam disk 247 carried by the shaft 46. The transverse movements are imparted to the looper by means of the block 234 which is rocked about a horizontal axis. The block is mounted on the frame of the machine by means of a rearwardly extending pin 248 formed on the block engaging an aperture in the frame. The slot 240 in the yoke 236 is elongated to permit the tail piece 242 on the looper carrier to work therein upon actuation of the block 234. The block 234 is actuated by means of a downwardly projecting arm 250 projecting therefrom which is provided with a cam roll 252 on its lower end engaging a cam groove in the cam disk 247. It will be noted that this mechanism for actuating the looper is simple and

compact in construction and operates the looper positively and smoothly.

The illustrated machine is provided with a take-up, a pull-off and a pair of thread locks, one of the thread locks being interposed between the take-up and the pull-off and the other thread lock being interposed between the pull-off and a wax pot 255. The wax pot is secured in a convenient position 5 on the front of the machine frame below the thread lock interposed between the pull-off and the wax pot and the needle thread passes directly from the wax pot to the thread lock.

The relative timing of the operation of the 15 take-up, pull-off and thread locks is such that the pull-off acts to pull thread from the supply while the take-up is actuated to give up thread to the stitch forming devices, and during the retracting movement of the pull-

20 off the taking up action of the take-up occurs. The take-up comprises a pair of rotatable disks 256, 258 which are centrally secured together by means of screws 260 threaded into the end of a rearwardly and upwardly inclined shaft 262 journaled in bearings 264 on the frame of the machine and held from longitudinal movement by means 25 of a collar 266 secured to the shaft and interposed between the brackets 264 (Figs. 5, 7, 30 11 and 12). The disks 256, 258 are provided with peripheral contacting ribs 268. The disk 258 is of resilient material and is provided with a series of equally spaced apertures which receive the ends of pins 270 carried by the disk 256, the annular space between the ribs 268 and the pins 270 forming a thread passage. The stretch of thread leading from one of the thread locks to the take-up disks passes over a thread truck 272

40 mounted on one end of a lever 274. The lever 274 is pivotally mounted on a cap screw 276 which is threaded into an axial aperture in the inclined shaft 262. In order that the thread truck 272 may be positioned substantially in alinement with the ribs 268, the disk 258 is cut away at 278. The disk 256 is provided with an elongated concentric slot 280 in which the stud that supports the thread truck 272 works. To take up the thread and 45 to set the stitch the take-up disks are rotated counter clockwise, and during this movement of the disks the lever 274 is carried therewith by the engagement of one end of the slot 280 with an extension of the stud 281 on which 50 the thread truck 272 is mounted. As the disks are thus rotated counter clockwise the thread is wound up on the disks and is forced down between the ribs 268 to engage the pins 270. To give up thread to the stitch forming

55 devices and loop-taker hereinafter described, the disks are rotated clockwise carrying the lever 274 therewith by the engagement of the other end of the slot 280 with the stud on which the thread truck 272 is mounted. During 60 the rotation of the disks to the right, the

stitch forming devices pull the thread from between the disks. The resistance offered by the ribs 268 to the passage of the thread between them results in a sufficient tension being placed on the thread to prevent any slack occurring. In order to set the stitch on the welt side, the thread is tensioned as the needle loop passes over the top of the bobbin case. This is accomplished by the end 282 of the lever 274 being carried by the disks against a yielding abutment near the limit of the rotation of the disks in a clockwise direction which arrests the movement of the lever relatively to the disks. This abutment comprises a bell crank 284 (Fig. 5) pivoted 70 at 286 on a bracket projecting from the frame of the machine. The bell crank is provided with an arm 288, the end of which is adapted to be engaged by the lever 274. The bell crank 284 is urged in a direction to resist the rotation of the lever 274 by means of a coiled spring 290 engaging the under side of the arm 288. The movement of the bell crank 284 by the spring 290 is limited by the engagement of a stop screw 292 threaded into a depending arm of the lever with a rigid abutment on the bracket that supports the bell crank lever. The amount of tension placed on the thread as it passes over the top of the bobbin case may be regulated by adjusting the stop screw 292. When the thread has passed over the top of the bobbin case, the take-up disks are rotated in a counter clockwise direction, the cycle of operations being 75 repeated. The take-up disks are oscillated as above described by means of a crank 294 that forms an extension of the crank 169 that actuates the awl. The connection between the take-up disks and the crank 294 comprises a pinion 296 (Fig. 7) formed on the forward end of the inclined shaft 262 which pinion is engaged by a gear segment projecting from a sleeve 298 pivotally mounted on a pin 300 secured to the frame. On the sleeve 298 is formed a bevel gear segment 302 80 which engages a gear segment 304 secured to a rock shaft 306 mounted on the frame. The rock shaft 306 is actuated by an arm 308 secured thereto which is connected by a link 310 with the crank 294 (Fig. 5). In the 85 operation of the take-up, the take-up disks are rotated in a counter-clockwise direction to take up the thread and then in a clockwise direction to give up the thread, as described. In the illustrated machine, the link 310 is actuated by the crank 294 and has a path of movement such that the take-up of the thread occurs while the crank 294 is rotating through an angle of approximately 70 degrees, and such that the giving up of the thread occurs during the remainder of the rotation of the crank, as will be apparent from an inspection of the drawings.

The pull-off comprises a thread truck 312 over which the stretch of thread extending 90

between the thread locks passes. The thread truck 312 is mounted on the upper end of a vertically sliding rack bar 314. Upon the upward movement of the bar 314, the thread 5 is pulled from the supply. Upon the downward movement of the bar the thread is given up to the take-up. The sliding bar 314 is actuated by the oscillating arm 308 that forms a part of the actuating mechanism for 10 the take-up. The connection between the bar and the arm 308 comprises a gear segment 316 (Fig. 5) secured to a rock shaft 318 which gear segment engages the gear teeth on the bar. The rock shaft 318 is actuated by an 15 arm 320 secured thereto which is connected by a link 322 with an arm 324 that constitutes an extension of the arm 308.

In order that the amount of thread measured off by the pull-off shall be in accordance 20 with the thickness of the work, the extent of movement imparted to the sliding bar 314 is controlled by the presser foot actuating mechanism. To this end the connection between the link 322 and the arm 324 is adjustable 25 lengthwise of the arm to vary the amount of movement imparted to the link by the arm and such adjustment is effected by mechanism connecting the link with the shaft 84 of the presser foot actuating mechanism. 30 The connection between the link 322 and the arm 324 comprises a block 326 pivotally mounted on the end of the link which block 35 engages a curved groove 328 extending longitudinally of the arm 324. The connection 35 between the link 322 and the shaft 84 comprises a link 330 which connects the link 322 with an arm 332 secured to the shaft 84.

The curvature of the groove 328 is such that when the pull-off is at the limit of its 40 retracting movement, the groove is concentric with the axis of the pivotal connection of the link 322 and the arm 320 so that the adjustment of the link 322 relatively to the grooved arm 324 varies the limit of the pulling-off 45 movement of the pull-off without varying the limit of the retracting movement of the pull-off. The pull-off is adapted to be adjusted independently of the presser foot actuating mechanism to vary the amount of thread 50 pulled from the supply. To effect such adjustment of the pull-off, the link 330 that connects the link 322 with the presser foot actuating mechanism is adapted to be adjusted longitudinally to vary the position of the 55 block 326 in the groove of the actuating arm 324. To enable the link to be thus adjusted, it is made in two sections which are adjustably connected by a turn-buckle 333.

The thread lock interposed between the 60 take-up and the pull-off is indicated at 336, and the thread lock interposed between the pull-off and the supply is indicated at 338 (Figs. 1, 5, 6, 7 and 11). While the take-up is being actuated to give up thread to the 65 stitch forming devices, the thread lock 336 is

closed and the thread lock 338 is opened to permit the pull-off to pull thread from the supply. During the taking-up action of the take-up the thread lock 336 is open and the thread lock 338 is closed to permit the take-up 70 to draw the stretch of thread taut that extends from the thread lock 338 to the work. The operation of the thread locks is so timed that the thread is held at all times by one or the other of the thread locks. The thread 75 lock 336 comprises a fixed jaw 340 and a movable jaw 342. The fixed jaw 340 is provided with a pair of spaced ears 344 having horizontal eyes through which the thread passes and the movable jaw 342 is arranged to 80 work between the ears 344. The fixed jaw 340 is secured to the frame of the machine and the movable jaw 342 is pivotally mounted upon the upper end of a lever 346 pivotally mounted at 348 on the frame. The thread 85 lock 338 comprises a fixed jaw 350 and a co-operating movable jaw 352, the jaw 350 being secured to the frame and provided with an ear 354 having an eye through which the thread passes, and the movable jaw 352 being 90 located adjacent the underside of the ear 354 and pivotally mounted on the upper end of a lever 356 which is pivoted on the frame. The lower ends of the levers 346 and 356 carrying the movable jaws are pivotally connected to 95 pins 358 secured to the bifurcated inner ends of sliding rods 360. The rods 360 are provided with reduced shank portions that extend through tubular bolts 362 threaded into 100 apertures in the frame. The rods 360 are urged in the direction to close the thread locks by means of springs 364 coiled about the rods and interposed between the bearing bolts 362 and shoulders formed on the rods. The rods 360 are moved in the opposite direction to open the thread locks in the proper 105 timed relation by means of cams 366 which act on cam rolls mounted on the bifurcated ends of the rods. The cams 366 are carried by the forward end of a rock shaft 368 journaled in the frame. The shaft 368 is actuated by means of an arm 370 (Figs. 1 and 6) secured to its rear end which arm is connected by a link 372 to a crank arm 374 carried by the main driving shaft 376 of the machine, 110 which shaft is journaled in the frame.

In order that the thread may be freely drawn from the supply when the presser foot is raised by the treadle rod 120 there is provision for opening the thread lock 338 upon the upward movement of the treadle rod to raise the presser foot. The connection between the thread lock 338 and the treadle rod 120 comprises an arm 378 (Figs. 1, 2, 4 and 5) having its free end bifurcated to embrace the shank of the rod 360 and to engage nuts 380 threaded on the outer end of the rod. The arm 378 is secured to the forward end of an inclined shaft 382. The rear end of the shaft 382 carries an arm 384, the free end of 115 120 125 130

which arm engages the under side of a lug 386 on the treadle rod 120.

The loop taker and bobbin case are mounted concentrically, the bobbin case being held 5 stationary and the loop taker being rotated about the bobbin case to pass the needle loop over the bobbin thread. In order that the loop taker may operate in proper timed relation with the other thread handling devices

10 of the machine, it is caused to make three revolutions during each cycle of operations of the machine. The loop taker comprises an annular gear 390 having peripheral gear teeth which mesh with the teeth of a gear 392

15 carried by an inclined continuously rotating shaft 394 journaled in bearings in the frame of the machine. The loop taker is mounted for rotation in a bearing formed in a bracket plate 396 which engages a central annular

20 groove in the teeth of the gear 390, the bracket plate being made in sections for convenience in assembling (Figs. 1 and 17). On opposite sides of the gear 390 are secured annular plates 398 by means of screws 400, which

25 plates extend slightly beyond the ends of the gear teeth. The bobbin case is held within the loop taker by the engagement of a peripheral flange or rib 402 near the forward open end of the bobbin case with a recess in the

30 loop taker formed by ribs 404 on the gear 390 and on the forward annular plate 398. The bobbin case is held stationary within the loop taker by the engagement of the lower ends of levers 406 with diametrically opposed notches

35 in the forward edge of the bobbin case.

The levers 406 are fulcrumed on a pin 407 secured to the frame and are held in engagement with the notches in the bobbin case by means of torsion springs 409 coiled about the

40 pin 407. In order that the needle loop as it is carried about the bobbin case by the loop taker may pass by the ends of the levers 406, the levers are alternately retracted from the bobbin case in the proper timed relation to the

45 travel of the needle loop. The levers are thus retracted by means of cams 411 carried by the shaft 394 which cams act on the upper ends of the levers, the upper ends of the levers being located at opposite sides of the shaft

50 394. The bobbin is mounted in the bobbin case on the usual split sleeve 408 projecting from the back wall of the bobbin case, and the bobbin case is provided with the usual slot 410 through which the thread passes from

55 the bobbin to the work. The needle loop is carried about the bobbin case by means of a transverse rearwardly inclined recess or slot 412 in the loop taker in which the transverse part of the loop is placed. The slot 412 ex-

60 tends between two adjacent teeth of the gear 390 and through the annular plates 398, the slot 412 extending inwardly beyond the gear teeth in order that the loop of thread may clear the bracket plate 396. The bracket

65 plate is cut away at 414 to provide an opening

through which the thread may be presented to and pass from the loop taker. The peripheries of the annular plates 398 are provided with bevelled portions 416 adjacent the rear wall of the slot 412 in order that the rear wall of the slot may project beyond the forward wall thereby forming a hook like projection which causes the thread to readily enter the slot.

The needle loop is engaged and spread 75 across the loop taker when the needle has reached the limit of its loop drawing stroke by means of a loop spreading arm 418 (Figs. 1 and 6). The loop spreading arm works

80 across the loop taker in a plane parallel to the path of the needle and in close proximity to the needle. The loop spreading arm is mounted in a split collar 420 formed on a rock

85 shaft 422 journaled at its ends on the conical ends of bearing screws 424 threaded through apertures in brackets projecting from the frame. The loop spreading arm is actuated by means of a gear segment 426 secured to the rock shaft 422 which engages teeth formed on

90 the forward end of a sliding bar 428, the rear end of which bar is provided with a cam roll 430 that engages a cam groove in a cam disk carried by a driving shaft 432 of the machine. The loop spreading arm is adjustable longitudinally and also toward and from the

95 needle so that it may be accurately positioned relatively to the needle. To this end the loop spreading arm is longitudinally adjustable in the split collar 420 and is adjustable toward and from the needle by adjustment of the

100 screws 424 on which the rock shaft 422 is mounted.

The main driving shaft 376 and its driving and stopping mechanism is located at the rear of the machine, and extends fore and aft of the machine. The driving shaft 376 is connected through spiral gears with the shaft

105 432 which actuates the loop spreading arm, the shaft 46 which actuates the needle, awl, take-up and pull-off mechanisms, and the shaft 394 which drives the loop taker. The shaft 432 is driven by a spiral gear 434 secured thereto which is engaged by a spiral gear 436 carried by the driving shaft 376.

The shaft 46 is driven by a spiral gear 438 secured thereto which is engaged by the spiral gear 434. The shaft 394 is driven by a spiral gear 440 secured thereto which engages the spiral gear 434. It will thus be seen that

110 the main driving shaft 376 drives the machine through an exceptionally smooth running mechanism, the parts of which mechanism take up a minimum amount of space.

The driving and stopping mechanism of the illustrated machine is simple and compact in construction and efficient in operation and is designed to stop the machine without undue shock or jar and with its parts in a predetermined position. This mechanism

115 comprises a high speed driving mechanism 120

130

and a low speed driving mechanism, the high speed mechanism acting to drive the machine during the normal operation thereof, and the low speed mechanism being thrown in when the high speed mechanism is thrown out, and acts first to reduce the speed of the machine and then to drive the machine at a low speed to stopping position.

The high speed mechanism comprises a continuously driven pulley 446 journaled on a bushing sleeve 448 which is mounted on the main driving shaft 376 and is interposed between a collar 450 formed on the shaft and a boss 452 on the frame of the machine. The low speed mechanism comprises a spiral gear 454 journaled on a sleeve 456 which is mounted on the shaft 376 and held from longitudinal movement between a sleeve 458 secured to the shaft and a shoulder 460 formed on the shaft. The spiral gear is held from longitudinal movement by being interposed between the sleeve 458 and a flange 462 formed on the rear end of the sleeve 456. The spiral gear 454 is continuously driven by the high speed pulley 446 through speed reducing mechanism. This mechanism comprises a worm 464 engaging the spiral gear 454 and carried by an inclined shaft 466 journaled in bearings on the frame. On the left hand end of the inclined shaft 466 is secured a bevel pinion 468 meshing with a bevel gear 470 secured to a shaft 472 journaled in bearings in the frame. A spur gear 474 is secured to the rear end of the shaft 472 which gear meshes with a spur gear 476 secured to the rear face of the high speed pulley 446.

The high speed driving mechanism is thrown in by means of a treadle mechanism at the base of the machine which acts to raise a treadle rod 478, the upper end of which is pivotally connected to the horizontal arm of a bell crank 480 pivotally mounted on a pin 482 secured to the frame. This upward movement of the treadle rod 478 acts through the bell crank 480 to release a positive stop hereinafter described for the driving shaft 376, and then acts to shift the high speed pulley 446 forwardly to bring a friction clutch surface on the forward face of the pulley into engagement with a friction clutch surface on the rear face of a clutch member 484 presently described. The high speed pulley is thus shifted by the engagement of the horizontal arm of the bell crank 480 with an adjustable abutment screw 486 on the horizontal arm of a bell crank 488 pivotally mounted on the pin 482. The bell crank 488 is in the form of a yoke having separated sections arranged at opposite sides of the bell crank 480. The sections are connected by transverse horizontal bars 489 at the end of the horizontal arm of the bell crank, the bars being separated to permit the horizontal arm of the bell crank 480 to work in the space between them. The abutment screw 486 is secured to the upper

bar 489. The vertical arm of the bell crank 488 carries studs or rolls 490 on its upper ends that engage slots in lugs 492 projecting from a disk 494. The disk 494 is held from rotary movement by the engagement of the lugs 492 with flattened surfaces at opposite sides of the bearing for the rear end of the shaft 376 and is mounted for longitudinal movement with the high speed pulley 446 by a peripheral flange 496 on the disk being interposed between a shoulder formed on an annular ring 498 secured to the high speed pulley and the rear side of the spur gear 476.

The clutch member 484 is interposed between the spiral gear 454 and the high speed pulley 446 and is threaded on square threads 500 formed on the driving shaft 376 adjacent the forward side of the collar 450.

Upon the engagement of the pulley 446 with the clutch member 484 the clutch member is rotated with the pulley and the screw threads 500 act to move the clutch member rearwardly until it engages the collar 450, whereupon driving connection is established between the high speed pulley and the driving shaft 376.

Upon releasing the treadle mechanism, a spring (not shown) connected with the treadle rod 478 acts to lower the rod, whereupon the high speed pulley 446 is shifted rearwardly out of engagement with the clutch member 484 and a brake shoe 502 is brought into engagement with the periphery of the clutch member. The high speed pulley is shifted rearwardly by the horizontal arm of the bell crank lever 480 being brought into engagement with an adjustable abutment screw 504 mounted in the lower transverse bar 489 on the horizontal arm of the bell crank 488. The connection between the treadle rod and the brake shoe 502 comprises a bar 506 which is made in two spaced sections that are centrally connected by a cross piece 507. The bar has its rear end pivotally connected to the depending arm of the bell crank 480 and supported at its forward end by a link 508 having one end pivotally connected to the bar and its other end pivotally connected to an arm 510 secured to a rock shaft 512 mounted in the frame. An arm 514 is pivoted on the shaft 512 which arm carries the brake shoe 502. Upon the downward movement of the treadle rod 478 the bell crank lever 480 acts to move the bar 506 forwardly to cause a lug 516 formed on the cross piece 507 to engage the lower arm of a toggle 518, the upper arm of which toggle is pivotally connected to the brake shoe carrying arm 514, and the lower arm of which toggle is pivotally connected to an upwardly spring pressed plunger 520. The plunger 520 comprises a rod which extends through an aperture 522 in the frame of the machine. The lower end of the plunger rod is guided by an adjustable bearing sleeve 524 threaded

130

into the lower end of the aperture. The plunger rod is urged upwardly by means of a spring 526 coiled about the rod and interposed between the upper end of the sleeve 524 and a shoulder formed on the rod. With this construction it will be apparent that the engagement of the lug 516 with the lower arm of the toggle 518 will act to straighten the toggle and raise the brake shoe into engagement with the clutch member 484. When the brake shoe has reduced the speed of the clutch member 484 below that of the driving shaft 376 the screw threads 500 on the shaft act to shift the clutch member forwardly to bring a friction surface on the forward face of the clutch member into engagement with the rear ends of a series of friction plugs 528 mounted to slide in apertures in the spiral gear 454. The engagement of the clutch member 484 with the friction plugs 528 acts to shift the plugs forwardly to bring their forward ends into engagement with a friction surface on the rear face of a disk 530 formed on the sleeve 458 which as hereinbefore described is secured to the driving shaft 376. The spiral gear 454 then acts through the engagement of the friction plugs 528 with the disk 530 and the clutch member 484 first to reduce the speed of the driving shaft and then to drive the shaft at a low speed. The continued application of the brake shoe 502 on the clutch member 484, after the speed of the driving shaft has been reduced to that of the spiral gear 454, acts to reduce the speed of the clutch member below that of the driving shaft, whereupon the screw threads 500 act to shift the clutch member rearwardly out of engagement with the friction plugs 528. The driving shaft, being thus freed from its driving mechanisms, is stopped in a predetermined angular position by the engagement of a lug 532 on the periphery of the disk 530 with a positive stop 534 (see Fig. 3).

The positive stop 534 comprises a block secured to the upper end of a downwardly spring pressed plunger 536. This plunger comprises a rod which extends through an aperture 538 in a carrier 540, and is urged downwardly by means of a spring 542 coiled about the rod and interposed between a shoulder formed at the upper end of the aperture and a head 544 formed on the lower end of the plunger. The carrier 540 is mounted to slide vertically in an aperture in the frame of the machine and is moved up and down through a limited distance during each rotation of the driving shaft 376 by means of a cam roll 546 mounted on the upper end of the carrier engaging a cam groove in the disk 530.

The downward movement of the carrier occurs as the stop lug 532 approaches the positive stop 534 so that the stop is carried out of the path of the stop lug during the normal operation of the machine. Upon the down-

ward movement of the carrier 540, after the driving shaft is disconnected from the spiral gear 454, the head of the stop carrying plunger 536 is brought into engagement with the roll 548 on the forward end of the bar 506 which prevents the stop 534 from being moved downwardly by the carrier out of the path of the stop lug 532 whereupon the stop lug engages the stop 534 to finally bring the machine to rest, the roll 548 having been positioned beneath the plunger 536 upon the forward movement of the bar 506 to apply the brake as previously described. Upon engagement of the stop 534 and the stop lug 532, the stop is caused by the upward pressure of the bar 506 to snap into a slot 545 in the periphery of the disk, the stop lug 532 forming the rear wall of the slot. The engagement of the stop 534 with the recess prevents the shaft from being turned in either direction. The portion of the periphery of the disk 530 adjacent the rear wall of the slot 545 is provided with a slight rise so that the engagement of the stop 534 with this portion of the disk cooperates with the brake shoe 502 to retard the rotation of the driving shaft after the low speed driving mechanism has been thrown out.

The brake shoe 502 is disengaged from the clutch member 484 just before the machine is stopped. This result is accomplished during the final downward movement of the carrier 540 which acts through the head of the plunger 536 and the roll 548 to swing the bar 506 downwardly a sufficient distance to cause an adjustable abutment screw 550 mounted on the cross piece of the bar to engage a tail piece 552 projecting from the lower arm of the toggle 518, thereby breaking the toggle to disengage the brake shoe from the clutch member.

Upon actuating the treadle mechanism to again start the machine the stop 534 is disengaged from the stop lug 532 before the high speed driving mechanism is thrown in. This result is accomplished during the first part of the upward movement of the treadle rod 478, the rod acting through the bell crank 480 to shift the bar 506 rearwardly to move the roll 548 thereon out of engagement with the head of the stop plunger 536, thereby permitting the plunger spring by depressing the plunger to disengage the stop 534 from the stop lug 532.

The illustrated stop mechanism is provided with means for unlocking and raising the presser foot upon stopping the machine and for unlocking the thread lock 338 that is interposed between the pull-off and the supply. To this end the rock shaft 512 has an arm 554 secured thereto, the free end of which is adapted to engage a lug 556 formed on an arm 558 having one end loosely mounted on the rock shaft 512 and its other end pivotally connected to the treadle rod 120 that is op-

eratively connected to the presser foot carrying lever and to the thread lock as hereinbefore described. Upon the downward movement of the bar 506 to disengage the 5 brake shoe from the clutch member 484, the bar acts through the link 508 and arm 510 to turn the rock shaft 512 in a direction to swing the free end of the arm 554 upwardly which acts through the lug 556 and arm 10 558 to raise the treadle rod 120 thereby unlocking and raising the presser foot and unlocking the thread lock. The treadle rod 120 is maintained in raised position while the machine is at rest by the engagement of the roll 15 548 on the forward end of the bar 506 with the head of the stop plunger 536.

Upon starting the machine into operation the treadle rod 120 is lowered to its initial position to permit the presser foot to be 20 locked in engagement with the work and to permit the locking of the thread lock. This result is accomplished by the disengagement of the roll 548 from the head of the stop plunger 536 to permit the stop 534 to be released 25 from the stop lug 532, as above described, preliminary to the throwing in of the high speed driving mechanism. The disengagement of the roll 548 from the head of the stop plunger 536 allows the spring 130 connected with the 30 treadle rod 120 to lower the rod to its initial position. During this downward movement of the rod 120, the rod acts through its connection with the bar 506 to raise the forward end of the bar to the position indicated 35 by dotted lines in Fig. 23.

In order that the treadle mechanism hereinbefore referred to connected with the treadle rod 120 may not interfere with the operation of the treadle rod by the stop 40 mechanism, the rod is made in two telescoping sections, the upper section being movable independently of the lower section and connected to the stop mechanism, and the lower section being connected to the treadle 45 mechanism. The upper end of the lower section of the rod extends into a sleeve 560 secured to or formed on the lower end of the upper section. Upon actuating the treadle mechanism to raise the lower section, the 50 upper section is raised by a collar 562 secured to the lower section, engaging the lower end of the sleeve 560. It will be apparent that the connection between the upper section and the rock shaft 512, comprising the arms 558 55 and 554, permits the upper section of the rod to be carried upwardly with the lower section independently of the stop mechanism, and permits the operation of the upper section by the stop mechanism independently of the lower section of the rod. 60

The machine illustrated in the drawings is adapted to be manually operated after the machine has been brought to rest by the stop mechanism, and a safety device is provided 65 to obviate any danger of the power driving

mechanism being thrown in while the machine is being thus operated. Preliminary to the manual operation of the machine the treadle rod 120 is lowered to permit the presser foot to be locked in engagement with the work to lock the thread lock and to release the positive stop 534 from the stop lug 532. This result is accomplished by raising the treadle rod 478 sufficiently to disengage the roll 548 mounted on the bar 506 from the 70 head of the stop plunger 536 and to bring the bar to the raised position indicated by dotted lines in Fig. 23 without raising the treadle rod sufficiently to throw in the driving mechanism. In order to prevent the power driving mechanism from being thrown in while the machine is being manually operated, means is provided for securely locking the bar 506 in its raised position and consequently locking the treadle rod 75 478 from movement. This means comprises a locking pin 564 mounted to slide in a bearing in the frame of the machine which pin is advanced, by mechanism hereinafter described, into engagement with an aperture 80 566 in the forward end of the bar 506.

The machine is manually operated by means of a hand wheel 568 mounted to slide on a bearing sleeve 570 secured to the frame of the machine and in which the left end of the driving shaft 432 is journaled. During the normal operation of the machine the hand wheel is disconnected from the driving shaft 432 and is held in position against a flange 572 formed on the inner end of the 100 sleeve 570 by the engagement of a spring pressed ball 571 mounted in the hub of the hand wheel with an annular groove 573 in the sleeve 570. When it is desired to operate the machine manually, the hand wheel is 105 connected to the driving shaft 432 so that upon rotating the hand wheel the driving shaft of the machine is rotated. To connect the hand wheel and the driving shaft 432, the hand wheel is moved outwardly on the bearing sleeve 570 to disconnect the spring pressed ball 571 from the groove 573 and to bring a hexagonal portion 574 of the inner wall of the hub of the hand wheel into engagement with a hexagonal surface 576 formed on a collar 110 secured to the extreme left end of the driving shaft 432. The hand wheel is held in this position by the engagement of the ball 571 with an annular groove 575 in the sleeve 570. During the outward movement of the hand wheel, the locking pin 564 is moved into engagement with the locking aperture in the bar 506 by mechanism connecting the hand wheel with the bar. This mechanism comprises a rack bar 578 mounted to slide in a bearing in the frame and having its outer end bent at right angles to engage an annular groove 582 in the hub of the hand wheel. The rack bar 578 is provided with gear teeth 115 120 125 130

that are engaged by a gear segment 584 secured to the upper end of a vertical rock shaft 586 mounted in the frame. The lower end of the rock shaft 586 carries a gear segment 588 that engages gear teeth formed on a side of the locking pin 564.

When it is desired to again throw in the power driving mechanism of the machine, the hand wheel 568 is moved inwardly which disconnects the hand wheel from the 10 shaft 432 and acts through the mechanism connecting the hand wheel to the locking pin 564 to disengage the locking pin from the bar 506, thereby releasing the treadle rod to permit the treadle mechanism for the 15 power driving mechanism to be operated.

The driving and stopping mechanism, the feeding mechanism, the shuttle mechanism, the take up mechanism and the presser foot 20 mechanism disclosed in the present application form the subject matter of divisional applications Serial No. 387,346 filed June 8, 1920, on which Patent No. 1,545,116 issued on July 7, 1925 and Serial Nos. 676,535, 676,536, 25 676,537, 676,538, filed November 23, 1923.

The nature and scope of the present invention having been indicated and a machine embodying the several features of the invention in their preferred form having been 30 specifically described, what is claimed is:—

1. A sewing machine having, in combination, stitch forming devices, and means for feeding the work in timed relation to the stitch forming devices comprising a work 35 support, a presser foot, and means for imparting work feeding and retracting movements to the work support and presser foot, and means comprising two relatively movable wedge blocks for locking the presser foot during the work feeding movement and for unlocking the presser foot during said 40 retracting movement of the work support and presser foot.

2. A sewing machine having, in combination, stitch forming devices, a work support, a presser foot, means for feeding the work, means comprising two relatively movable wedge blocks for locking the presser foot during the feeding operation and for unlocking the presser foot during the retraction of 45 the work feeding means, and means comprising a relatively light spring for holding the presser foot in engagement with the work independently of the wedge blocks during said retraction of the work feeding means.

3. A sewing machine having, in combination, a thread lock, a work support, a presser foot, means for locking the presser foot in engagement with the work, means for unlocking the presser foot, a rod for retracting the 50 presser foot from the work support and for unlocking the thread lock upon movement of the rod in one direction, means acting automatically to move the rod in said direction 55 upon stopping the machine, and means com-

prising a manually operated means to move the rod in said direction.

4. An outsole lock stitch shoe sewing machine having, in combination, stitch forming devices, a presser foot, an edge gage adapted to be moved into and out of operative position, and a work support having provision for adjustment transversely of the direction of feed in the plane of the work supporting surface of the work support.

5. A sewing machine having, in combination, a needle and an awl laterally immovable, actuating mechanisms therefor, work feeding devices comprising a work support, a presser foot, and mechanism operating to actuate the presser foot to clamp the work on the work support, then to actuate the work support and presser foot to feed the work, then to cause the presser foot to lightly engage the work, and then to retract the work support and presser foot while the presser foot lightly engages the work and while the needle is in the work, a needle guide, and means for advancing the needle guide to a position substantially in engagement with the work during said retraction of the work support and presser foot.

6. A lock stitch sewing machine having, in combination, stitch forming devices including a curved hook needle, a curved awl, and means for actuating the needle and awl comprising a continuously rotating shaft, a pair of cranks carried by said shaft, and connections between the cranks and the needle and awl respectively.

7. A lock stitch sewing machine having, in combination, stitch forming devices including a curved hook needle, a curved awl, a loop taker, a take-up, means for actuating the take-up, means for actuating the awl comprising a continuously rotating crank, and connections between the crank and awl acting to impart an idle backward and forward movement to the awl at the limit of its retracting movement, and means for actuating the needle comprising a continuously rotating crank, and connections between the crank and needle acting to impart an idle backward and forward movement to the needle at the limit of its work piercing stroke.

8. A lock stitch sewing machine having, in combination, a needle, and needle actuating mechanism acting to impart an idle backward and forward movement to the needle at the limits of both strokes of the needle.

9. A lock stitch sewing machine having, in combination, stitch forming devices including a curved hook needle, needle actuating mechanism comprising a continuously rotating crank, and connections between the crank and needle constructed and arranged to impart an idle backward and forward movement to the needle at the limit of its work piercing stroke.

10. A lock stitch sewing machine having, in combination, stitch forming devices including a curved hook needle, means for feeding the work comprising a work support, a presser foot, and means for imparting a work feeding movement to the work support and presser foot while the needle is out of the work and for imparting a retracting movement to the work support and presser foot while the needle is in the work, and means for actuating the needle comprising a continuously rotating crank, and connections between the crank and needle constructed and arranged to maintain the needle substantially stationary at the limit of work piercing movement.

11. A lock stitch sewing machine having, in combination, a curved hook needle, a curved awl laterally stationary, means for feeding the work, and means for actuating the needle and awl comprising continuously rotating cranks, and lever and link connections between the cranks and the needle and awl.

12. A lock stitch sewing machine having, in combination, a curved hook needle, a curved awl, a take-up, a pull-off, a continuously rotating shaft, and cranks carried by the shaft for actuating the needle, awl, take-up and pull-off.

13. A lock stitch sewing machine having, in combination, a curved hook needle, a curved awl, a pull-off, a continuously rotating shaft, and cranks carried by the shaft for actuating the needle and pull-off.

14. A lock stitch sewing machine having, in combination, a curved hook needle, an awl, a pull-off, a continuously rotating shaft, and cranks carried by the shaft for actuating the needle, awl and pull-off.

15. An outsole shoe sewing machine having, in combination, a needle, an awl, actuating mechanism for the awl, a work support, a presser foot, means for actuating the work support and presser foot to feed the work while the needle and awl are out of engagement with the work and for retracting the work support and presser foot while the needle is at the limit of its work piercing movement, and actuating mechanism for the needle acting to impart an idle backward and forward movement to the needle at the limit of its work piercing stroke, the start of the backward and forward movement of the needle occurring at the start of the retraction of the work support and presser foot and ending at the limit of the retraction of the work support and presser foot.

16. An outsole shoe sewing machine having, in combination, a needle, an awl, actuating mechanism for the awl, a work support, a presser foot, means to actuate the work support and presser foot to feed the work while the needle and awl are out of engagement with the work and for retract-

ing the work support and presser foot while the needle is at the limit of its work piercing stroke, and mechanism for actuating the needle acting to retract the needle slightly during the retraction of the work support and presser foot.

17. A sewing machine having, in combination, a curved hook needle, a channel knife, carriers for the needle and knife movable about a common axis, means for actuating the needle carrier, and means for actuating the knife carrier to move the knife into and out of operative position and retain the knife in either position during the continued operation of the machine.

18. A sewing machine having, in combination, a curved hook needle, a curved awl, a channel knife, carriers for the awl and knife mounted for movement about a common axis, means for actuating the awl carrier, and means for actuating the knife carrier to move the knife into and out of operative position and retain the knife in either position during the continued operation of the machine.

19. A sewing machine having, in combination, a curved hook needle, a channel knife, carriers for the needle and knife, an edge gage pivotally mounted on the knife carrier, means for actuating the needle carrier, and means for actuating the knife carrier and for turning the edge gage about its pivot on the carrier to move the knife and edge gage into and out of operative position.

20. A sewing machine having, in combination, a curved hook needle, an edge gage, a carrier for the needle, a carrier for the edge gage on which the edge gage is pivotally mounted, and means for actuating the needle carrier, and means for actuating the edge gage carrier and for turning the edge gage about its pivot on the carrier to move the edge gage into and out of operative position.

21. A sewing machine having, in combination, a looper, a curved hook needle, and a thread arm to cooperate with the looper to lay the thread in the barb of the needle mounted for movement about the axis of the needle movement.

22. A sewing machine having, in combination, a curved hook needle, a curved awl, a pair of supporting arms, carriers for the needle and awl arranged side by side between the supporting arms, a hub formed on the awl carrier journaled in one of the supporting arms, a pin extending through an axial aperture in the awl carrier, adjustable longitudinally therein and having a conical inner end on which the needle carrier is journaled, and a hub formed on the needle carrier journaled in the other supporting arm.

23. A sewing machine having, in combination, a curved hook needle, a curved awl, a looper, a pair of supporting arms, carriers for the needle and awl arranged side by side between the supporting arms, a hub formed

- on the awl carrier journaled in one of the supporting arms, a pin carried by the awl carrier and having a conical inner end on which the needle carrier is journaled, a sleeve 5 journaled in the other arm, a thread arm carried by the sleeve to cooperate with the looper to lay the thread in the barb of the needle, and a hub formed on the needle carrier journaled in said sleeve.
- 10 24. A sewing machine having, in combination, a work support, a presser foot, means to actuate the work support and presser foot to feed the work, an edge gage, and means for simultaneously retracting the edge gage and 15 adjusting said actuating mechanism for the work support and presser foot to vary the length of the feed.
- 20 25. A sewing machine having, in combination, work feeding means, an edge gage, a channel knife, a manually operable lever, and means actuated by the lever for simultaneously 25 moving the channel knife and edge gage relatively to the work and for adjusting the work feeding means to vary the length of the feed, and means for operatively disconnecting the lever from the work feeding means to permit the edge gage and channel knife to be moved independently of the work feeding means.
- 30 26. A sewing machine having, in combination, a work support, a presser foot, means for actuating the work support and presser foot to feed the work, a channel knife, and means for simultaneously retracting the 35 channel knife and adjusting said actuating mechanism for the work support and presser foot to vary the length of the feed.
- 40 27. A sewing machine having, in combination, a curved hook needle, a curved awl, actuating mechanism for the needle and awl, a looper, looper actuating mechanism, a thread arm to cooperate with the looper to lay the thread in the barb of the needle, said needle, awl and thread arm being mounted for rotary reciprocating movements about a common axis, and means for reciprocating the thread arm comprising a gear segment on which the thread arm is mounted, a pinion 45 engaging the gear segment, a lever having a gear segment on one end engaging the pinion, and a cam for actuating the lever.
- 50 28. A sewing machine having, in combination, stitch forming devices including a hook needle, a looper acting to lay the thread in the barb of the needle, and means for actuating the looper comprising a looper carrying lever, a pivoted block on which the lever is pivotally mounted, means for turning the block about its pivot to impart a movement to the looper in one direction, and a cam and suitable connections for moving the looper lever about its pivot to impart a movement to the looper in a transverse direction, 55 said connections being arranged to permit movement of the pivoted block independently of said connections.
29. A sewing machine having, in combination, stitch forming devices including a hook needle, a looper acting to lay the thread in the barb of the needle, and means for actuating the looper comprising a looper carrying lever, a pivoted block on which the looper lever is pivotally mounted, means for turning the block about its pivot to impart a movement to the looper in one direction, and means comprising a yoke separate from the lever and embracing the block for moving the looper lever about its pivot to impart a movement to the looper in a transverse direction. 70
30. A lock stitch sewing machine having, in combination, stitch forming devices including a needle, a loop taker, a take-up, a pull-off, a thread lock interposed between the take-up and the pull-off, a thread lock interposed between the pull-off and the thread supply, one of said thread locks comprising a pair of thread gripping jaws, a lever on which one of the jaws is pivotally mounted, and means comprising a cam for actuating the lever to open and close the jaws in timed relation to the actuation of the take-up, pull-off and the other thread lock. 80
31. A lock stitch sewing machine having, in combination, stitch forming devices, a take-up, a pull-off, mechanism for moving the pull-off in a direction to draw thread from the supply and in the opposite direction to give up the thread, said mechanism having provision for adjustment to vary the limit of the first movement of the pull-off in accordance with variations in the thickness of the work while the limit of the second movement of the pull-off remains fixed. 85
32. A lock stitch sewing machine having, in combination, stitch forming devices, a take-up, a pair of thread locks, a pull-off comprising a longitudinally movable bar working between the thread locks, a thread truck mounted on one end of the bar over which the stretch of thread extending between the thread locks passes, means for moving the bar in a direction to draw thread from the supply and in the opposite direction to give up thread to the take-up, said actuating means for the bar having provision for adjustment to vary the limit of the movement of the bar in the direction to draw thread from the supply while the limit of the bar in the opposite direction remains fixed. 95
33. A lock stitch sewing machine having, in combination, stitch forming devices, a take-up, mechanism for actuating the take-up comprising a continuously rotating crank, and connections between the crank and take-up, a pull-off, and connections between the pull-off and the actuating mechanism for the take-up for actuating the pull-off. 105
34. A lock stitch sewing machine having, 110
35. A lock stitch sewing machine having, 115
36. A lock stitch sewing machine having, 120
37. A lock stitch sewing machine having, 125
38. A lock stitch sewing machine having, 130

in combination, stitch forming devices, a take-up, a pull-off comprising a reciprocatory bar having rack teeth thereon, a thread truck mounted on the bar over which the thread 5 passes, and mechanism for actuating the bar comprising a rock shaft, a gear segment secured to the rock shaft engaging the gear teeth on the bar, an arm secured to the rock shaft, a lever, a link connecting said arm and 10 one end of the lever, a continuously rotating crank, and a link connecting the other end of the lever and said crank.

35. A lock stitch sewing machine having, in combination, stitch forming devices, a take-up, a pull-off, means for actuating the pull-off comprising a rock shaft, an arm secured to the rock shaft, a link, connection between one end of the link and the arm, means for operatively connecting the other end of the 15 link with the pull-off, the connection between the link and rock shaft having provision for adjustment to vary the amount of movement imparted to the pull-off, and means for adjusting said connection to vary the amount of 20 movement imparted to the pull-off in accordance with variations in the thickness of the work.

36. A sewing machine having, in combination, a needle and an awl laterally immovable, actuating mechanism therefor, work feeding mechanism, and a channel knife fixed in the direction of feed arranged to cut a channel in the work as the work is fed past the knife.

35 37. An outsole shoe sewing machine having, in combination, stitch forming devices, means for feeding the work in timed relation to the stitch forming devices comprising a work support, a presser foot and means for 40 imparting work feeding and retracting movements to the work support and presser foot, and a channel knife fixed in the direction of feed arranged to cut a channel in the work as the work is fed past the knife.

45 FRED ASHWORTH.
